(57) **CLAIM**

The ornamental design for a rotating laser, as shown and described.

DESCRIPTION

The article is a rotating laser which a laser beam is scanned in the predetermined plane by rotation of a prism, a reflector or the like so that a standard plane is presented by the scanning rotating laser beam. A body of the rotating laser has an operating section, a cap of battery box and a pair of grips on the side thereof. A bottom of the rotating laser has a tripod mounting screw at the center of the bottom. The body of the rotating laser has a laser projecting section which is mounted on a top of a rotating cylinder. The grips function to protect the operation section. Three legs are provided at a rear side so that the rotating laser can be used sideways. A guard roof of the rotation laser is openly mounted on the top of the body.

FIG. 1 is a front, upper and right perspective view of the rotating laser, according to my novel design;

FIG. 2 is a rear, upper and right perspective view of the rotating laser of FIG. 1;

FIG. 3 is a front view of the rotating laser of FIG. 1;

FIG. 4 is a rear view of the rotating laser of FIG. 1;

FIG. 5 is a left side view of the rotating laser of FIG. 1;

FIG. 6 is a right side view of the rotating laser of FIG. 1;

FIG. 7 is a top plan view of the rotating laser of FIG. 1; and,

FIG. 8 is a bottom view of the rotating laser of FIG. 1.
